Inventor.

UNITED STATES PATENT OFFICE.

RICHARD HENRY ADAMS, OF COBALT, ONTARIO, CANADA.

PERCUSSIVE ROCK-DRILLING APPARATUS.

1,403,583.

Specification of Letters Patent. Patented Jan. 17, 1922.

Application filed October 4, 1918. Serial No. 256,822.

To all whom it may concern:

Be it known that I, RICHARD HENRY ADAMS, of the town of Cobalt, in the district of Nipissing, and Province of Ontario,

5 Dominion of Canada, have invented certain new and useful Improvements in Percussive Rock-Drilling Apparatus; and I hereby declare that the following is a full, clear, and exact description of the same.

10 This invention relates to a percussive rock drilling apparatus containing certain novel features of construction which permit of greatly-increased efficiency with corresponding advantageous operation, and it relates 15 more particularly to the rotating device by which the piston can be caused to revolve during the operation of the drill; the general subject matter of this invention being disclosed in Patent No. 1,269,147.

20 In the drawings:

Fig. 1 is a sectional elevation of the cylinder and its related parts;

Fig. 2, is a sectional elevation of the cylinder with the piston removed;

25 Fig. 3, is a sectional plan view of the ratchet wheel and forks, and,

Fig. 4, is a detail view of one of the forks.

30 Fig. 5, is a sectional view showing one of the pawl carrying forks and a fragment of the ring.

Like characters of reference refer to like parts throughout the specification and drawings.

35 *a* represents the cylinder; *b* represents a jacket surrounding the cylinder *a*, and forming with it an exhaust chamber *c*; and *d* represents an air chest, integral with, or attached to the jacket *b*, provided with an 40 air intake *e*.

In the back cylinder head *k'* and in line with the inlet port *i'*, is an air chamber *g*, the bottom of which is formed by a block *q''*, having a set of diagonally-arranged 45 ports *q'* through which the air is delivered from the air chamber on the back piston head *r*, which is provided with a turbine or rotating device *r'*. The delivery of the air against the back piston head *r* causes the 50 axial and rotating movement of the piston as hereinafter described. Between the spaced piston heads *r* and *s* the piston is formed with a set of spiral grooves *t'*, axially of the piston, and encircling the piston 55 ton is a ring *t''*. The inner face of the ring *t''* is provided with projections *t³*, which en-

ter the spiral grooves *t'* to cause the step by step rotation of the piston. The outer surface of the ring is provided with ratchet teeth *v* engaged by pawls *v'* which permit 60 of the forward rotation of the ring and piston and prevent their reverse rotation. The pawls *v'* are carried by forks *v''* extended through the cylinder from the exterior of the apparatus, the forks engaging the ring 65 *t''* to prevent its movement axially of the cylinder during the reciprocation of the piston, and the pawls engaging the ratchet teeth and permitting of the forward, and preventing the reverse, rotation of the ring 70 and piston. By this means, a partial rotation of the piston may be effected at each stroke.

If the drill should not be required to rotate step by step during the reciprocation 75 of the piston, the forks *v''* and pawls *v'* may be withdrawn, and in that case, the ring *t''* can reciprocate with the piston, without affecting its motion.

For the down stroke of the piston, compressed air is admitted from the air chest through the port *i'* into the air chamber *g* from which it is discharged through the diagonal ports *q'* against the turbine or rotating device *r'* of the piston head *r*. The 85 impact of the air on the turbine tends to cause the rotation of the piston, and the expansion of the air causes its down stroke.

The projections of the ratchet wheel are 90 continuously in the spiral grooves of the piston, and when the ratchet wheel is prevented, by the forks, from moving axially with the piston, these projections and spiral grooves permit only of a step by step rotation of the piston. When the ratchet wheel 95 is released, by the withdrawal of the forks, it moves axially with the piston, and the latter can then continuously revolve during its reciprocation in both directions due to the momentum resulting from the action of 100 the compressed air on the turbine, the inertia being sufficient to carry the rotation through the upward stroke. In this way the piston may be selectively permitted to 105 rotate either step by step or continuously during its reciprocation. When the piston reaches the limit of its down stroke, its action is reversed by compressed air admitted to the cylinder through the port *i'*.

What I claim is:

110 1. In a percussive rock drilling apparatus, the combination of a cylinder, a rotary-

reciprocating piston therein having its circumferential wall spirally grooved between the piston heads, a ratchet ring encircling the piston having ratchet teeth on its outer surface and projections on its inner surface engaging in the spiral grooves of the piston, removable forks extending through the cylinder wall to engage said ring and prevent its reciprocating movement, and 5 detent pawls carried by the forks engaging the ratchet teeth to permit of the rotation of the ring in one direction and resist its rotation in the opposite direction when the forks are engaged therewith, said ring being free 10 to reciprocate with the piston when the forks are removed from the cylinder.

2. A percussive drilling apparatus comprising a cylinder, a rotary-reciprocating piston therein having its circumferential wall spirally grooved between the piston heads, a ratchet ring encircling the piston between the piston heads and having internal members entered in the spiral grooves of 20 the piston, removable forked means extending through the cylinder wall engaging the ratchet ring and preventing its reciprocation when engaged therewith, and ratchet means combined with said removable means engaging with the ratchet ring for the step by step rotation of the piston, the removal of 25 said means releasing the ratchet means from the ratchet ring for free movement with the piston, and means for introducing a motive agent into the cylinder externally at opposite ends of the piston for its actuation.

tation of the piston, the removal of said 30 forked means releasing the ratchet means from the ratchet ring for free movement with the piston.

3. A percussive rock drilling apparatus, comprising a cylinder, a rotary-reciprocating piston therein having its circumferential wall spirally grooved between the piston heads, a ratchet ring encircling the piston between the piston heads and having internal members entered in the spiral grooves of 35 the piston, removable forked means extending through the cylinder wall engaging the ratchet ring and preventing its reciprocation when engaged therewith, ratchet means combined with said removable forked means 40 engaging with the ratchet ring for the step by step rotation of the piston, the removal of said means releasing the ratchet means from the ratchet ring for free movement with the piston, and means for introducing 45 a motive agent into the cylinder externally at opposite ends of the piston for its actuation.
